[57] **CLAIM**

The ornamental design for a dispenser for assorted office articles, as shown and described.

DESCRIPTION

FIG. 1 is a top plan view of a dispenser for assorted office articles showing my new design;

FIG. 2 is a front elevational view, the rear elevation being a mirror image thereof;

FIG. 3 is a right side elevational view, the left side being a mirror image thereof;

FIG. 4 is a bottom plan view;

FIG. 5 is a top plan view of a second embodiment of my new design;

FIG. 6 is a front elevational view of FIG. 5, the rear elevational view being a mirror image thereof;

FIG. 7 is a right side elevational view of FIG. 5, the left side being a mirror image thereof; and

FIG. 8 is a bottom plan view of FIG. 5.

FIG. 1.

FIG. 2.

FIG. 3.

FIG. 4.

FIG. 5.

FIG. 6.

FIG. 7.

FIG. 8.
